Specification of Letters Patent.

Patented Apr. 21, 1914.

Application filed December 21, 1908. Serial No. 468,637.

To all whom it may concern:

Be it known that I, HENRY C. OSBORN, a citizen of the United States, residing at Cleveland, in the county of Cuyahoga and 5 State of Ohio, have invented a certain new and useful Improvement in Type Setting and Distributing Machines, of which the following is a full, clear, and exact description, reference being had to the accompanying drawings.

The object of this invention is to provide a simple and efficient type case with keyboard mechanism for assembling type therefrom or distributing it therewith,— 15 either or both. The mechanism is particularly well adapted for setting or distributing small type wherein all the characters have the same thickness, as, for example, imitation typewriter type.

20 The invention comprises, in one aspect, a type storage member having a plurality of type holders, a keyboard having keys corresponding to the different holders and an intermediate carrier adapted to be controlled by the keys in a movement between the assemblage or distribution position and the different holders of the storage member.

Various features of the invention contributing to the efficiency are included 30 within this invention, wherefore the invention may be best summarized as comprising the combinations of coöperating parts described or illustrated herein and set out in 35 the claims.

The particular embodiment shown is designed to operate with type having grooved sides and beveled feet such as shown and claimed in Patent No. 836,026 of H. C. 40 Gammeter.

Figure 1 is a plan partly sectional of my machine; Fig. 2 is a sectional side elevation of the same; Fig. 3 is an enlarged detail of the escapement mechanism and its operating mechanism shown on smaller scale in Fig. 2; Fig. 4 is a sectional plan near the rear end of the machine showing the operating rock shafts and universal bars; Fig. 5 is a side elevation of the shiftable carriage 45 taken from the opposite direction to Fig. 2; Fig. 6 is a front elevation of such carriage; Fig. 7 is an enlarged detail of the pivoted support for the shuttle bar; Fig. 8 is a detail of the interlock for the keys, being an

enlarged front elevation of such mechanism 55 shown in section in Fig. 2; Fig. 9 is a side elevation of the carriage and coöperating parts as used when the machine is distributing; Fig. 10 is a front view of the mechanism shown in Fig. 9; the remaining views 60 are details in perspective, Fig. 11 being the shuttle bar; Fig. 12, one of the plungers carried thereby; Figs. 13 and 14, the two dogs of the escapement; and Fig. 15, the type which this embodiment of the machine 65 carries.

Referring by reference numerals to the embodiment shown in the drawing, 1 represents a bed plate, from the rear side of which rise standards or brackets 2 and 3, 70 and an intermediate standard 4. The type case proper consists of two storage members which are shown as segments 10 and 11. These segments are stiffened by suitable ribs as 12 and are carried on the frame 75 standards 2 and 3 by vertical rods 13 and 14, there being two rods for each segment. These rods occupy eyes in the segments and standards and serve to rigidly hold the segments in place. The upper ends of the rods 80 are preferably knurled as shown at 15 in Fig. 2, wherefore they may be conveniently drawn out of the segments to allow their removal. Each of the segments is provided with suitable means for holding vertical rows of 85 type. As shown, this means consists of ribs or rails 17 and 18 on the two segments respectively. Each rail has an overhanging edge whereby undercut channels are provided between successive rails, which channels are adapted to be occupied by type 90 20 grooved on its opposite sides, and as is shown, for example, in Fig. 15.

Near the lower ends of the segments 10 and 11 they are each provided with a series 95 of escapements, one for each type channel. These escapements operate to normally hold the type above them in the channel, but when operated, are adapted to release the lowermost type. Each escapement in the 100 form shown includes a dog 25 (Figs. 3 and 13) pivoted at 26 and having a nose 27 adapted to engage beneath the type and forced in such direction by a spring 28, and a second dog 29 (Figs. 3 and 14) pivoted 105 at 30 and having a nose 31 adapted to engage beneath the next to the bottom type and a spring 32 tending to force this dog

away from the type. The dog 25 has a lip 33 which is adapted to be engaged and operated by the rear portion 34 of the dog 29. The dogs are thin metal plates and take up little room. This escapement is designed to operate on type having transversely beveled feet, as shown in the drawing. Normally the spring 28 holds the dog 25 with its nose 27 beneath the line of type, supporting the line. The dog 29 is held by the spring 32 with the nose 31 far enough in the rear to clear the line. When it is desired to release a type, suitable mechanism, to be hereinafter described, lifts the dog 29. This movement causes the nose 31 to engage beneath the next to the bottom type, while the continued elevation of this dog by reason of the shoulder 34 abutting the lips 33 withdraws the dog 25, releasing the bottom type. In this movement, the parts have changed from the position shown in the right hand escapement in Fig. 3 to that shown in the left hand escapement.

It will be seen from the above description that by simply raising and lowering the dog 29, the type will be released one at a time and allowed to drop by gravity. The mechanism which causes the operation of the dogs and that which receives the released type is controlled by the keyboard and its connections, which will now be described.

Pivotaly mounted on a cross web 6 rising from the base plate are the key levers 40 which have finger keys 41 at their forward ends. The web 6 is preferably arc-shaped concentric with the drums, and the key levers occupy radial positions, being guided near their outer ends by a suitable comb 42 mounted on another arc-shaped frame web 40. The right hand half of the keyboard constitutes one bank, and the left hand half a separate bank of keys. Each bank has the rear end of its levers 40 projecting beneath a universal bar 44 or 45. Each of these two universal bars are arc-shaped concentrically with the segments and project forwardly from two alined horizontal rock shafts 50 and 51 carried near the rear of the machine by the standards 2, 3 and 4. As shown, the rear ends of each universal bar are bent toward the corresponding rock shaft and are there adjustably secured by screws 52 to arms 53 and 54 rigid on the corresponding rock shafts. The rock shafts are shown as journaled in the standard 4 and as having their outer ends carried by movable studs 56 which are held by set screws 57 in the standards 2 and 3 respectively.

Loosely mounted on the two rock shafts 50 and 51 between the standard 4 and the adjacent arms 54 are a pair of upwardly extending arms 60 and 61. At their upper ends, these arms are formed into pins or studs 62 and 63 respectively, which are guided in a forward and back path by slots

64 in a forward extension 8 of the stand 4. Above this extension 8 is a shuttle bar 70 which extends forwardly beneath the two segments 10 and 11 and is pivoted at the axis of those segments. This pivot in the form shown is made by a stud 71 carried by the frame plate 8 (Fig. 7), which has a reduced upper extension 72 on which the shuttle bar is journaled. Resting on this extension and above it, is the plug 73 clamped by a set screw 74. As shown in Fig. 2, this plug has a knurled upper end 75 whereby it may be conveniently removed when the set screw 74 is loosened, thus allowing the shuttle bar to be taken out. The shuttle bar 70 is of the form shown in Fig. 11, though when assembling it carries a pair of plungers omitted in distributing and not shown in that view. The bar is provided near its rear end, forward of its pivot, with two inclined slots 77 and 78 which cross the slots 64 in the frame plate 8. The pins 62 and 63 accordingly, if moved rearwardly in their slots 64, will engage the rear wall of the slots 77 or 78, as the case may be, and swing the shuttle in one direction or the other. The arms 60 and 61 carrying these pins are connected by yielding connection with the two universal bars 44 and 45. This is shown as accomplished by extending upwardly the two arms 54 in the form of bell cranks 57 which carry at their upper ends adjustable studs 58 which extend through lips 68 on the arms 60 and 61, there being springs 59 surrounding the studs in front of the lips, which springs are compressed by heads 56 on the studs.

It results from the above described construction that whenever any of the keys in the right hand bank, for example, in the keyboard is depressed, the universal bar 45 is thereby elevated, rocking the shaft 51 and rocking rearwardly the arms 57 and 61 causing the pin 63 on the latter to bear against the rear wall of the slot 78 and thereby swing the shuttle bar 70 toward the right. Similarly, when any of the left hand bank of keys are depressed, the universal bar 44 is lifted and the pin 62 is moved rearwardly which, operating on the inclined rear wall of the slot 77 swings the shuttle bar to the left.

The amount of swing of the shuttle bar varies with the position of the different keys,—these farther from the center line of the machine acting on a portion of the universal bar nearer the rock shaft and thus causing greater movement,—so that the shuttle bar tends to swing somewhat beyond a position directly over the key actuated. Suitable stops are provided operated by the various keys, which arrest the movement of the shuttle bar when it comes beneath the type channel corresponding to the given key and thereafter a continued move-

ment of the key is allowed by reason of the spring 59 which becomes further compressed. This stop mechanism and mechanism concurrently operated to actuate the escape-
5 ments will now be described.

Standing over each key lever and at the rear of its pivot is a lifter bar 80 which is made preferably in the form shown in Fig. 3, with an approximate T-head. These 10 lifter bars are guided near their lower ends by extending into openings in a stationary plate 81, which may be carried by a suitable comb like standard 9 which separates and guides the rear ends of the key levers. At 15 its upper end, the lifter plate is guided by two pins 83 and 84 which operate through openings in a pair of arc-shaped plates 86 and 87 which lie directly beneath the type channels of the two drums and extend a distance below them only slightly in excess of 20 the thickness of the shuttle bar 70,--the shuttle bar having substantially the thickness of a type. The lifter bars are also guided near their upper ends by upwardly 25 extending projections 88 thereon which occupy radial notches in the forward edge of the arcual plate 86. Suitable springs 90 serve to normally depress the lifter plates and consequently maintain the keys elevated. 30 These springs are shown as surrounding the pins 83.

The projections 88 are adapted to stand in the path of the forward end 79 of the shuttle bar 70, and as the corresponding projection is elevated every time a key is depressed, and as such depression swings the shuttle bar in that direction, it will be seen that the shuttle bar comes to rest abutting the corresponding projection 88. This 40 brings the openings 91 and 92 in the shuttle bar directly beneath the type channels holding type corresponding to the key depressed. These openings are preferably of the same shape as the type. The springs 59 heretofore described allow further depression of the keys and consequently further elevation of the lifter bars after the shuttle bar has so stopped, and this further elevation causes one or the other of the shoulders 94 and 95 45 on the lifter bar to operate one or the other of the plungers 97 and 98, carried by the shuttle plate, when the machine is assembling (as hereinafter explained), whereby 50 one or the other of the corresponding dogs 55 29 is raised, releasing the lowermost type of the corresponding channel, which thereupon drops by gravity into the opening 91 or 92 below such channel. Now when the pressure on the finger key is released, the spring 60 47 acting on the corresponding universal bar or rock shaft rocks that shaft to swing the corresponding pin 62 or 63 forwardly, which by engaging the front wall of the slot 77 or 78 returns the shuttle bar to central 65 position, and after it has come into that po-

sition moves slightly forward alongside of the bar to hold it there. During this movement of the bar, the type entrained in the opening 91 or 92 has been slid along on the plate 86 or 87. When the type is brought 70 to the central position, it comes over an opening 96 or 99 in these two arc-shaped bars whereby it drops into one or the other of these openings. When the machine is arranged for assembling, there are beneath these openings two receiving channels 100 and 101 carried by blocks secured to the under sides of the arcual plates, and from these channels the type passes by gravity into the common receiving channel 110 80 which is shiftable to align with either of the channels 100 or 101 and from this common receiving channel the type pass down by gravity into the central receiving typeholder 111, which is shown as a split tube, the 85 edges of which are adapted to receive the side grooves of the type.

The position of the common receiving channel 110 to align with either of the channels 100 or 101 in assembling is controlled 90 by shift keys, which mechanism determines also which plunger 97 or 98 is operated by the lifter bar and accordingly whether type is released from the channel of the outer drum or the inner drum. It is to be understood that the channels of the two drums which are in the same radial plane contain characters which have some relation to each other, either an intrinsic relation, as capitals and small letters, or a relation depending on 100 convenience of grouping. The same key releases type from either of the two channels according to the shifting mechanism, shown as operated by two shift keys. This will 105 now be described:

The temporary typeholder 111 into which the type is adapted to be assembled and which furnishes the means for conveying it to a suitable printing press or otherwise, as desired, is held in alinement with the common channel 110 by having its upper end enter a socket in a forward and downward projection 120 of a carriage 121, the holder being held in its socket by a spring retainer 122. The carriage 121, shown more particularly in Figs. 5 and 6, is an upright member extending forward and back of the machine at its center and slidably guided on a stationary support 123 carried by the bed plate 1.

The support 123 is preferably U-shape, as shown, and the lower end of the carriage extends between the two side plates of the member and has a ball bearing thereon, the balls occupying raceways between the outer 125 sides of the carriage and the inner sides of the stationary side plates. These balls are shown at 124 in Figs. 2 and 6. They may be surrounded by a suitable retainer 125 which is allowed a limited movement, by 130

means of a pin and slot, equal to half the movement of the carriage.

The carriage supports the type holder 111 and when used for assembling, has its upper end abutting the lower ends of the channels 100 and 101, as shown in Fig. 2. With the parts in the position shown in this figure, the channel 101 is blocked, while the channel 100 is in alignment with the common channel 110.

If the carriage were in its rear position, the channel 101 would align with the channel 110. To effect such movement of the carriage, I provide the lever 128 pivoted to one of the sides of the support 123 and having a pin and slot connection at its upper end with the carriage. The lever has arms 129 and 139 extending in opposite directions from its pivot. Suitable adjustable stop screws 130 are adapted to be engaged by one arm or the other respectively and limit the movement of the lever and hence the carriage. A spring 131 anchored to the bed plate and to the lever above its pivot tends to hold the lever in either extreme position, and swing it into that position after the lever has been swung from the other direction past the center. The lever accordingly holds the carriage in either extreme position.

To swing the lever from either position it may occupy into the other position, and thereby shift the carriage, I provide a pair of shift keys. These keys are located at the central portion of the key board on opposite sides of the temporary typeholder, and are pivoted on a suitable stationary standard 135. One of the keys 136 is shown as extending inwardly beyond the pivot and 40 extending below a lip 138 on the lever arm 139, whereby the depression of a key may elevate that arm and swing the lever into its rearmost position. On the other hand, the other shift key 141 extends downwardly from its pivot as shown at 142, and bears against an upwardly extending arm on a lever 143 normally held upward by a spring 144. This lever extends rearwardly and overhangs the lip 138 so that the downward movement of this shift key is adapted to force downward the lever arm 139 and bring the carriage into its foremost position. It will thus be seen that in whichever position the carriage is, it may be shifted into the other extreme position by the operation of the corresponding key. As soon as the shift has moved the carriage slightly over half the distance, the spring 131 acts and completes the movement. This spring holds the carriage in either extreme position until the shift key is operated to move it to the other extreme position.

The shifting of the carriage not only brings the common channel 110 into alignment with either the channel 100 or the chan-

nel 101, but it also operates to change the presentation of the plungers 97 and 98 to the lifter bar so that the other one of these plungers is engaged. These plungers 97 and 98, (one of which is shown in perspective in Fig. 12) are cylindrical so that they may be turned in their housings 89, by which they are mounted on the shuttle bar, but the lower portions thereof are cut in half vertically and they are so positioned that if the plunger is turned with half cylindrical projection crosswise of the lifter bar, it may be engaged by that bar to lift the same, whereas if it is turned with the cut diameter parallel with the lifter bar, it will be out of alignment with the lifter bar and the lifter bar when lifted will move in said cut-out portion of the plunger and not acuate said plunger.

When the carriage is in its foremost position, the plunger 97 has its lower end standing crosswise of the lug 94 on the lifter bar, as shown in Fig. 3, while the plunger 98 has its lower end parallel with the lug 95 of the lifter bar. In this position, therefore, when the bar is lifted, the plunger 97 is lifted to operate the dog of the outermost segment, while the plunger 98 is idle, the lifting bar moving simply past it. Springs 150 on these plungers tend to keep them depressed. Each plunger is provided with laterally extending pins 151, as shown in Figs. 1, 5 and 12. The carriage has suitable fingers 152 adapted to engage these pins as the carriage moves. Now, with the parts as shown in Figs. 2 and 3, if the carriage is shifted rearwardly, these fingers 152 will engage the pins 151 and rock the two plungers so that the plunger 97 will be turned to clear the lug 94 while the plunger 98 will stand across the lug 95 and so will be raised by it. The plunger is centered in either of its two positions by the pin 154 carried thereby entering a notch 155 (Fig. 3) in the upper face of the housing. Accordingly, the keys operate to release the type only in that segment with which the typeholder is communicating and when the shift is operated to change the typeholder to communicate with the other segment, the release mechanism is correspondingly shifted.

To prevent any jamming resulting from the attempt to operate more than one key at a time, I provide suitable interlocking mechanism. This mechanism, which is shown in Figs. 2 and 8, may conveniently consist of a series of movable distance pieces 160 held in a guideway in the front side of the frame member 7 and behind the comb 42. The distance pieces are beveled or cut off at their upper corners 161, and above this cut out space and substantially over the line between the distance pieces stand the various key levers, 40, etc. The blocks 160 are loose, having a longitudinal play which

is slightly greater than the width of a key lever, but is not as great as the width of two keys levers. Accordingly, when any key lever is depressed, it forces sidewise the two blocks beneath it and enters the space between the adjacent flat sides of these blocks, as illustrated in one instance in Fig. 8. When the key lever is in this position, all of the space between the blocks is appropriated, and none of the other key levers can be depressed.

A very simple change of adjustment in the mechanism adapts it to be used as a distributing machine, conveying type from the typeholder 111 to any of the channels in the segments, as desired. When used as a distributing mechanism, I replace the shuttle bar 70, provided with the plungers 97 and 98, by a similar bar without these plungers, by loosening the set screw 74 and raising the plug 73; and I remove the two blocks carrying the channels 100 and 101, which I have described as secured on the underside of the arc-shaped members 86 and 87, and in place of these supply a block 170 held to the carriage on its upper end and having a channel 172 alining with the channel 110, and taking the place of both the channels 100 and 101; I provide means for feeding the type in the holder 111 toward the upper end of the holder, advancing the entire column of type, one type at a time, through pawls and a ratchet, this feed being accomplished through the operation of the finger keys; and I shift the comb 42 to bring the deeper portion 171 of the slots therein (which portion is idle during assemblage) beneath the key levers so that these levers may obtain a further stroke.

The substitute parts are shown in Figs. 9, 10 and 11. The type are fed upward in the temporary type holder by means of a follower 174, to which is attached a cord 175 passing around the pulley 176 and secured to a sheave 177 which is fast on the side of a ratchet wheel 178. This ratchet wheel is rigidly mounted on a stud 179 journaled in a plate 180 projecting forwardly from the block 170 and attached thereto. The ratchet wheel is given a partial rotation whenever a key is depressed by means of the driving pawl 182 pivoted on the upper end of the bell crank 183 which is mounted on a boss projecting from the forward flange of the carriage 121, the rear arm of the bell crank 183 extending through a slot in the flange alongside the boss on which the bell crank is mounted. The boss, constituting part of the carriage, appears in Fig. 2 but not the bell-crank, pawl or ratchet as they are removed when assembling. Projecting in both directions from the center line of the machine and in a horizontal plane directly above the plane of the universal bars 44 and 45 when they are in their normal positions,

are pins 184 and 185 carried by the shorter arm of the bell crank. It will be seen, therefore, that on the depression of any key in either of the banks the bell crank 183 will be rocked, through the engagement of either of the yokes 44 or 45, with the pin 185, when the carriage is in its forward position, or pin 184 when the carriage is in its rear position.

The forward end of the driving pawl 182 is provided with an inclined lip 186 which engages a projection 187, formed integral with the supporting plate of the feeding mechanism, and such engagement tends to withdraw the driving pawl 182 from the tooth of the ratchet. A pawl supporting arm 188 also projects from plate 180 and carries two pawls 189 and 190, 189 being shorter than the pawl 190 by one half the length of a ratchet tooth. A spring 191 attached at one of its ends to the stud 179 passes about the stud and is secured at its other end to plate 180. This spring, assisted by the weight of the column of type turns the ratchet in the opposite direction to that given it by the pawl 182. A spring 192 is employed to return bell crank 183 to its normal position after it has been swung by the depression of any of the key levers.

The operation of the distributing mechanism is as follows:—Upon the depression of any key, one or the other of the universal bars 44 or 45 is swung upwardly carrying with it either one of the pins 184 or 185, whichever the case may be, and thus swinging the upper end of the bell crank 183 forwardly. The driving pawl 182 being attached thereto and engaging one of the teeth of the ratchet, rotates the ratchet until the projection 187, through its engagement with the inclined lip 186, has completely freed the pawl from the teeth of the ratchet, when the ratchet will return a distance permitted by one of the detent pawls 189 or 190. The inclined lip 186 is of such a length that it will permit of the rotation of the ratchet until the pawls 189 and 190 have passed nearly the distance of one tooth. At this position of the parts, the column of type has been advanced until one type rests within the opening 91 or 92 in the shuttle bar, being supported in such a position by the next type below it, which is in the opening in the arc-shaped plate 86 and 87. The further movement of the key, which swings the shuttle bar 70 to the type channel corresponding to the key depressed, continues the forward movement of the pawl 182 until it is entirely freed from the ratchet, and allows the ratchet wheel to return until stopped by one of the detent pawls, such backward movement of the ratchet being a distance equal to just one half of a tooth, owing to the proportions of the detent pawls 189 and 190. This allows the type formerly supporting

the type within the shuttle bar and resting within the opening in the plates 86 and 87 to drop from this opening until it is beneath the lower plane of the same and the carriage can be shifted without the uppermost type interfering with such operation. Up to this time in the operation of the distributing mechanism, the key has been depressed the normal amount used in assembling. By reason of the comb 42 having been shifted, a greater movement is allowed, and this continued movement by the key levers down the slots 171, further elevates the lifter bar and causes the pin 83 or 84, as the case may be, to shove the type in the shuttle bar upward into the type channel above the nose 27 of the dog 25, the dog simply swinging back to allow the type to pass this nose. When the key is released, the lifter bar descends, the dog holding the new type, and the shuttle bar returns to normal position. During this operation, the universal bar 44 or 45 has released the bell crank 183, and pawl 182 resumes its normal position and engages the next tooth of the ratchet wheel.

Having thus described my invention, what I claim is:

1. In a typesetting and distributing machine, the combination of a storage member having typeholders, a key board, and intermediate mechanisms controlled thereby common to the various typeholders and traveling transversely thereof and interchangeable to distribute type into the storage member and assemble type from it.

2. In a typesetting and distributing machine, the combination of an upright segmental storage member having typeholders, a key board, and oscillatable traveling mechanism controlled thereby and adapted to convey type toward and from a position in registration with a given holder of the storage member, and means for releasing type in the storage member and allowing it to drop into the traveling mechanism.

3. The combination of an upwardly extending storage member having type channels, means for releasing type from the lower end thereof, means for feeding type upwardly into the lower end thereof, and an oscillatable laterally moving type shifter common to both of said means and common to the various type channels.

4. The combination of an upright stationary storage member, means for releasing type from the lower end thereof, means for feeding type upwardly into the lower end thereof, and movable means common to the various type holders and interchangeable for conveying such type to and from said member.

5. The combination of a type case having a set of typeholders, a co-operating type conveyer common to the various holders and

having an opening to receive type, a stationary support for such type during the movement of the conveyer, and a keyboard adapted to move the conveyer various amounts.

6. A type case having a plurality of parallel longitudinal channels adapted to confine type having feet beveled in a direction which is transverse to a composed line of such type, escapements engaging the bevel of said feet, a co-operating type conveyer, and a keyboard adapted to move the conveyer various amounts.

7. The combination of a type case formed of a plurality of concentric segments, a conveyer adapted to co-operate with each segment, and a keyboard adapted to move the conveyer various amounts.

8. The combination of a type case, a co-operating type conveyer having an opening adapted to entrain type, a stationary support which such type contacts with and rests upon during the movement of the conveyer, and a keyboard adapted to move such conveyer various amounts.

9. The combination of a segmental type case, a co-operating oscillating conveyer having an opening adapted to entrain type, an arecal plate over which said opening swings and on which the type rides during the swinging, and means for moving such conveyer various amounts.

10. The combination of a type case, a co-operating shuttle bar adapted to convey type and having an edge at an angle to the bar, a driving arm working against said edge to swing the shuttle bar, and a keyboard having finger keys adapted to move the driving arm.

11. The combination of a type case, a co-operating type conveyer bar having transverse slots, arms working in said slots, and a keyboard arranged in two banks, the keys of one bank operating on one arm and those of the other bank on the other arm.

12. A type case made in the form of a segment of a drum, a type conveyer pivoted on the axis of such segment, and a system of key levers arranged radially on stationary pivots and adapted to move the conveyer various amounts.

13. The combination of a type case formed of a plurality of concentric segments, a pivoted conveyer adapted to co-operate with each segment, and a radially arranged keyboard adapted to move the conveyer various amounts.

14. A type case composed of a plurality of concentric segments, and a shuttle bar pivoted at the axis of said segments and having a plurality of openings adapted to receive type from the segments respectively.

15. The combination of a type case formed of a plurality of concentric segments, a pivoted conveyer adapted to co-operate

- with all of the segments, a keyboard adapted to move the conveyer various amounts, and a typeholder movable to coöperate with either segment.
- 5 16. A type case composed of a plurality of concentric segments, and mechanism, for operating on the type, pivoted at the axis of said segments.
- 10 17. The combination of a type case formed of a plurality of concentric segments, a pivoted conveyer adapted to coöperate with all of the segments, a keyboard adapted to move the conveyer various amounts, a typeholder movable to coöperate with either segment, and a shift key and mechanism controlled thereby for causing such movement.
- 15 18. A type case composed of a plurality of concentric segments having typeholders, mechanism for operating on the type pivoted at the axis of said segments, and shift mechanism to determine which of the segments is active.
- 20 19. The combination of a type case, a co-operating conveyer adapted to move back and forth across the end of the type case and having an opening adapted to carry but a single type, a plate on the other side of the conveyer along which it slides and which forms a guide for the type in the opening, and means for moving the conveyer various amounts.
- 25 20. The combination of a type case arranged in a plurality of concentric banks, an oscillatable type conveyer, a keyboard co-operable with either bank and adapted to oscillate said conveyer various amounts, and a shift for determining the bank with which the keyboard is coöperating.
- 30 21. The combination of a type-case, in the form of a drum segment, a pivoted shuttle bar having a pair of transverse diagonal slots, a pair of arms working in said slots to swing the bar in one direction or the other, a pair of universal bars connected with said arms, respectively, and a divided keyboard, one part of which operates one of the universal bars and the other part of which operates the other.
- 35 22. The combination of a stationary segmental typeholder having channels, individual escapements for various channels, an oscillating type carrier adapted to coöperate therewith, an escapement-operating plunger carried thereby, and a finger key for oscillating the type carrier.
- 40 23. The combination of a segmental type case having a plurality of parallel type holders, an oscillating type carrier adapted to swing across the ends of said typeholders, means for forcing type from the carrier into any of the holders, a keyboard of keys, and mechanism controlled thereby to swing the carrier various distances.
- 45 24. The combination of a type case having a plurality of typeholders, a type carrier having an opening, a stationary support on which the type in the opening slides when the carrier moves, a keyboard of finger keys, and mechanism controlled thereby for moving said carrier into coöperation with various of said typeholders.
- 50 25. The combination of a series of parallel typeholders, individual escapements therefor, interchangeable type carriers adapted to move across the ends of the typeholders, means adapted to coact with the escapements for releasing type from any of the holders into one of such carriers, means for forcing type from the other of such carriers into any of the holders, and a keyboard of finger keys for moving either carrier and operating such releasing and forcing means.
- 55 26. The combination of a segmental type case, a coöperating oscillating conveyer pivoted at the center of curvature of the type case, means for moving said conveyer from a central position in either direction varying amounts and back, an opening through the conveyer, and a stop plate on the opposite side of the conveyer forming the guide along which the opening travels, said stop plate having a central discharge opening.
- 60 27. The combination of a series of parallel typeholders, a type carrier in the form of a flat plate adapted to move across the ends of said typeholders over a smooth plate, means for releasing type from any of the holders into an opening in the carrier, and a set of finger keys for causing the movement of the type carrier varying amounts.
- 65 28. The combination of a series of parallel type holders, a type carrier adapted to move across the ends of said typeholders, and comprising a plate having a type receiving opening, a stationary plate below the plate mentioned adapted to support the type in such opening, and means for moving said carrier.
- 70 29. The combination of a type case having channels side by side, a member adapted to move across the ends thereof from one channel to the next and having an opening to receive type, and a smooth plate on the other side of the member adapted to support the type being moved, there being a space to allow the type to pass beyond the last-mentioned plate.
- 75 30. The combination of a series of parallel typeholders, a type carrier adapted to move across the ends of said typeholders and having an opening to receive type therefrom, an escapement for each holder comprising a pair of independently pivoted spring-pressed dogs, and a set of finger keys for causing the movement of the type carrier varying amounts and for automatically operating the escapement of the selected typeholder.
- 80 31. The combination of an upright type

case having a plurality of vertical typeholding channels, a shuttle bar adapted to be moved beneath the various channels, a keyboard, means controlled thereby for moving 5 said bar, said bar having a type holding opening, and a type supporting plate beneath said bar and over which such opening moves.

32. The combination of a type case in the 10 form of a segment of a drum of parallel type channels, a type conveyer in the form of a bar pivoted on the axis of such segment and having an opening adapted to align with any type channel, a system of key levers and 15 coacting mechanism arranged to swing the conveyer various amounts, and a common type channel on the opposite side of the conveyer.

33. The combination of an upright drum 20 segment having parallel longitudinal typeholders, a type carrier beneath the segment adapted to receive type dropped by gravity, a stationary member for supporting type in the carrier, and a keyboard for releasing 25 type and moving the carrier.

34. The combination of a type case in the form of a drum segment, a keyboard having key levers radially arranged with reference to the same axis, a shuttle bar pivoted substantially on the same axis and adapted to coöperate with said drum and be controlled by said keys, said bar having a type receiving opening, and a stationary arc-shaped type supporting plate just below the path of said opening.

35. The combination of a type case having channels, individual escapements for the various channels, a carrier, means for moving it across the end of the type case, 40 mechanism for operating the escapement of the channel opposite which the carrier stands, and a finger key for moving the carrier and operating the escapement.

36. The combination of a type case having 45 a plurality of typeholders, a type carrier having an opening for a single type, a guide on the opposite side of the carrier against which type in the opening may slide when the carrier moves, a keyboard having 50 finger keys, and mechanism controlled thereby for moving said carrier into coöperation with various typeholders.

37. The combination of a type case in the form of a drum segment, a carrier pivoted substantially on the axis of the segment, a keyboard having radially arranged key levers, a universal bar operated by said levers, mechanism controlled by said universal bar for swinging said carrier opposite 60 a corresponding typeholder, and suitable stops operated by said key levers individually to accurately position the carrier.

38. The combination of a type case having 65 a plurality of type holders with individual escapements, a movable conveyer, a

series of lifter bars for accurately limiting the movement of the same and concurrently operating said escapements, and a keyboard having keys adapted to operate the various lifter bars.

39. The combination of a type case having 70 a plurality of type holders, an individual escapement for each holder, a shuttle adapted to receive the released type, a series of lifter bars for operating the escapements, 75 and a keyboard adapted to operate the various lifter bars and the shuttle.

40. The combination of a type case having 80 a plurality of type holders, an individual escapement for each holder, a series of lifter bars for operating the escapements, a keyboard adapted to operate the various lifter bars, and a movable type conveyer to receive type released by said escapements, 85 said lifter bars accurately limiting the movement of the conveyer.

41. The combination of a type case having 90 a plurality of typeholders; an individual escapement for each holder, a series of lifter bars, a keyboard adapted to operate the various lifter bars, and a movable type carrier to receive type released by said escapements, 95 said type carrier carrying a plunger adapted to communicate motion from the lifter bar to the selected escapement.

42. The combination of a type case having 100 a plurality of banks of typeholders, individual escapements for the holders of the different banks, a keyboard wherein one key corresponds to typeholders of both banks, 105 a movable conveyer controlled by the keyboard, and carrying mechanism adapted to coact with the escapement for releasing type and having an opening to receive such released type, and a shift mechanism for determining which bank is operative.

43. The combination of a type case made 110 in the form of a plurality of concentric typeholding segments, a keyboard and coöperating interchangeable assemblage and distribution mechanism, means for removably holding the segments in the machine.

44. In an interchangeable typesetting and distributing machine, the combination with 115 a frame of an upright typeholding drum segment removably carried by the frame, a keyboard, a carrier swinging beneath the segment, mechanism operated by the keys for swinging the carrier, and lifter bars and associated mechanism operated by the keys 120 for moving the type up and down.

45. In an interchangeable typesetting and distributing machine, the combination with 125 a frame of an upright typeholding drum segment carried by the frame, a keyboard having key levers, a carrier swinging beneath the segment and having assemblage and distribution members, mechanism operated by the key levers for swinging the carrier, and lifter bars located over the re- 130

spective key levers and engaged and raised by them to operate said members.

46. In a typesetting or distributing machine, the combination with a frame of an upright typeholding drum segment removably carried by the frame, a keyboard having key levers projecting beneath said segment, a carrier swinging beneath the segment, mechanism operated by the keys for swinging the carrier, lifter bars operated by the keys for stopping the carrier, individual escapements for the different typeholders, mechanism carried by said carrier for operating the various escapements, and means whereby the lifter bars may operate said mechanism.

47. The combination of two type cases, a type carrier adapted to coöperate with either case, means for releasing type from either 20 case, a typeholder, means for shifting it to coöperate with either case, and means whereby said shift renders one of the releasing means idle.

48. The combination of two type cases, individual escapements therefor, a type carrier adapted to coöperate with either case, a pair of plungers on said carrier for operating the escapements of either case, a typeholder, means for shifting it to coöperate 30 with either case, and means whereby said shift renders one of the plungers idle.

49. The combination of a type case having a plurality of banks of typeholders, a carrier adapted to coöperate with all of 35 the banks, individual escapements, plungers carried by the carrier for operating the different escapements, and means for rendering active that plunger which coöperates with the selected case, the other plunger being 40 idle.

50. The combination of an upright stationary type case, interchangeable means including a carrier having an opening traveling over a type support for assembling type 45 from one end thereof and distributing type into the same end.

51. The combination of a type case, mechanism for assembling type therefrom, a keyboard for operating the same, interchangeable 50 mechanisms whereby type may be distributed into said case by the same keyboard, and means for varying the throw of the keys for assembling and distributing respectively.

52. In a type distributing machine, the combination of a type case, means for releasing type from the lower end thereof, a typeholder located below the same, means for feeding a line of type upwardly in the 60 holder, and means for conveying the type from the upper end of the holder to any of several receptacles in the type case.

53. The combination of a type case having parallel typeholding channels, a type 65 conveyer below the type case, a common chan-

nel leading upwardly to the conveyer, means for feeding type upwardly in said channel into the conveyer, a keyboard for moving said conveyer, the common channel being carried in a movable carriage, and a shift key for moving said carriage. 70

54. The combination of a type case having a plurality of typeholding channels, escapements therefor, means for operating said escapements to assemble type from the case, 75 and interchangeable means for distributing type and feeding such type into that end of the case past the escapements.

55. The combination of a type case having a plurality of banks of holders, a common typeholder, a shiftable carriage carrying said holder and adapted to cause it to communicate with either bank, and a pair of shift keys for shifting such carriage from one extreme position to the other respectively. 80

56. The combination of a type case arranged in a plurality of banks, a movable conveyer, a plurality of mechanisms mounted on said conveyer for releasing type from 90 each bank, finger keys, lifter bars, and means for causing the same to engage one mechanism and miss the other, as desired.

57. A type case composed of a segment of a drum having parallel longitudinal channels, a shuttle bar extending across the end of the drum, a lateral slot in such shuttle bar, a finger guided transversely of the slot whereby the movement of the finger may swing the shuttle bar, and means for moving said finger. 95

58. The combination of a segmental typeholding drum, a shuttle bar adapted to oscillate across the end of the same, radially arranged keys and key levers, an arcual universal bar, and mechanism controlled thereby for moving said shuttle bar varying amounts. 105

59. The combination of a pair of concentric segments, each having longitudinal rails for holding grooved type, and a coöperating shuttle bar having a pair of openings to receive such type. 110

60. The combination of a stationary upright segment provided with parallel longitudinal rails for holding grooved type and a pivoted shuttle bar extending across the lower end of such segment and having an opening to receive such type. 115

61. The combination of a stationary upright segment provided with parallel longitudinal rails for holding grooved type and a pivoted shuttle bar extending across the lower end of such segment and having an opening to receive such type, and an arcual supporting plate lying under the path of such opening. 120

62. The combination of a frame, a pair of concentric segmental typeholders, two pairs of removable through bolts for holding said 125

- segments in place, and a shuttle bar mounted to swing across one end of both segments and having two type-receiving openings.
63. The combination of a segmental type-holder, a pivoted shuttle bar coöperating therewith, said shuttle bar being formed with a pair of diagonal slots in its opposite edges, and a pair of arms pivoted on an axis at right angles to the axis of the shuttle bar and occupying said slots to swing the bar in one direction or the other.
64. A type-case for type having beveled feet comprising a plurality of rigidly held rails providing type channels, and an escapement for each channel consisting of a pair of dogs mounted side by side and co-operating with the beveled foot of the lowermost and next to the lowermost type.
65. The combination of a type-case having a plurality of channels, an escapement for each channel, a movable conveyer, means carried by the conveyer for operating the escapement, and means for moving the escapement-operating means to idle position.
66. The combination of a type-case having separate banks of channels for upper-case and lower-case type, individual means for releasing type from each channel, a pair of members for operating the releasing means of the two banks respectively, and means for concurrently rendering either member active and the other idle.
67. The combination of a pair of type-cases, a movable conveyer coöperating with both cases, two members carried by the conveyer for causing the release of type from the two cases respectively, and means for alternatively rendering either of said members active and the other idle.
68. The combination of a pair of type-cases, each case having a plurality of channels with individual escapements, a pair of plungers for operating such escapements respectively, and means for individually moving either plunger to render it inoperative.
69. The combination of a pair of type-cases, each case having a plurality of channels with individual escapements, a conveyer coöperating with both cases, a pair of plungers mounted on the conveyer for operating the escapements of the two cases respectively, and means for turning the plungers on their axes to render one idle and the other active.
70. The combination of a pair of type-cases, each case having a plurality of channels with individual escapements, a conveyer coöperating with both cases, a pair of plungers mounted on the conveyer for operating the escapements of the two cases respectively, means for turning the plungers on their axes to render one idle and the other active, a typeholder shiftable to coöperate with either case, and means whereby such shifting turns the plungers on their axes as stated.
71. The combination with a plurality of type-cases, a typeholder adapted to coöperate with each case, a shiftable carriage in which said typeholder is mounted, a shift key for shifting the carriage in one direction, and a second shift key for returning it to initial position, the carriage being adapted to stand in either extreme position.
72. The combination of a plurality of type cases, a carriage shiftable below the same to coöperate with either case, a typeholder mounted on said carriage, and means for feeding type upwardly along said typeholder.
73. The combination of an upright type-case, mechanism for assembling type from the lower end thereof, and interchangeable mechanism for distributing type into such lower end having means for feeding type upwardly and for then transferring it laterally beneath the proper holder and for then feeding it upwardly into the proper holder, each holder being provided with an escapement allowing the type to pass it upwardly and restricting the downward passage to one type at a time.
- In testimony whereof, I hereunto affix my signature in the presence of two witnesses.
